UNITED STATES PATENT OFFICE.

CHRISTIAN HIERING AND ALBERT FULLER, OF NEWARK, NEW JERSEY.

DESIGN FOR A BAG-HANDLE CAP.

No. 39,283.

Specification for Design.

Patented April 28, 1908.

Application filed January 15, 1907. Serial No. 352,463. Term of patent 3½ years.

To all whom it may concern:

Be it known that we, CHRISTIAN HIERING and ALBERT FULLER, citizens of the United States, residing in the city of Newark, in the county of Essex and State of New Jersey, have invented a new, original, and ornamental Design for Bag - Handle Caps, of which the following is a specification, reference being had to the accompanying drawings, forming a part thereof.

The figure is a perspective view of a bag handle cap embodying our new design.

We claim:

The ornamental design for a bag handle cap, as shown.

CHRISTIAN HIERING.
ALBERT FULLER.
